UNITED STATES PATENT OFFICE.

ELIJAH ETTER, OF PALMYRA, ILLINOIS.

DESIGN FOR TYPE.

SPECIFICATION forming part of Design No. 22,656, dated August 1, 1893.

Application filed March 7, 1893. Serial No. 465,031. Term of patent 14 years.

To all whom it may concern:

Be it known that I, ELIJAH ETTER, a citizen of the United States, residing at Palmyra, in the county of Macoupin and State of Illinois, 5 have invented a new and original Design for Stamps, of which the following is a specification.

My invention relates to a new and original design for type.

10 In the drawing—I have illustrated a perspective view of a type embodying my design.

15 1 designates the type-body, and 2 the face upon which is formed a series of parallel bars 3, slightly elevated above the face, and also a similarly elevated diagonal bar 4, the latter extending from one corner to a diagonally opposite corner of the field or series of bars.

What I claim is—

The design for type herein shown and described, the same consisting of a series of 20 parallel bars, and a diagonal bar crossing the series of parallel bars and extending from corner to corner of the field or series, substantially as specified.

In testimony that I claim the foregoing as 25 my own I have hereto affixed my signature in the presence of two witnesses.

ELIJAH ETTER.
